UNITED STATES PATENT OFFICE.

CHARLES SINGER, OF WINFRED, SOUTH DAKOTA.

STORM-WINDOW.

1,111,621.

Specification of Letters Patent. Patented Sept. 22, 1914.

Application filed February 16, 1914. Serial No. 819,012.

To all whom it may concern:

Be it known that I, CHARLES SINGER, a citizen of the United States, residing at Winfred, in the county of Lake and State of South Dakota, have invented certain new and useful Improvements in Storm-Windows, of which the following is a specification.

In many parts of this country, especially those parts subject to excessive cold and storms, what are commonly known as storm windows are extensively used. These windows are generally of the type auxiliary to the regular windows of a house, being adapted for detachment from the window frame after the winter season is over, and to be readily placed in position at the beginning of cold weather. The storm windows at present in use usually comprise a frame which is hung by hinges from the upper end of the main window frame, at the outside of the window exterior to the regular sashes, the lower end of the storm window being adjustable inward and outward by suitable locking means. Storm windows of this type are frequently entirely torn from their anchorage on the main window frame by high winds and sudden storms, or if not entirely blown off the storm window is often damaged by banging against the side frame or the walls of the house to which the window is applied.

My primary object in the present invention has been to devise a comparatively simple and cheap construction of storm window not only adapted to be placed in position from the outside of the house but also from the inside, while the usual storm window can only be placed in position from the outside of a dwelling. In addition to this, I contemplate the provision of a storm window which is made in sections, said sections each comprising virtually a window sash and one of them being relatively movable after the manner of a sliding sash in an ordinary window.

By reason of the peculiar construction of my storm window wherein opening of the window is effected by a sliding action of one of its sections, the liability of the window being torn from the main window frame is entirely avoided. My storm window has been constructed also with a special view of facilitating not only the placing of the same in position, and removal thereof, but to increase the portability of the auxiliary win-

dow, the last mentioned advantage being afforded by reason of its sectional construction and means whereby the sections may be folded one upon the other, or entirely separated from one another as may be desired. Owing to the folding capabilities of my storm window as well as the separability of the sections, considerable convenience is afforded as the window can be readily handled by women or young boys, a feature of primary importance.

Not only is the window hereinafter described adapted for use for storm purposes as hereinbefore premised, but the same is virtually a handy window that might be used generally if desired in the construction of certain kinds of dwellings. Especially would it be advantageous in connection with portable houses, summer cottages and the like. Furthermore the invention is susceptible in its principle of construction and action of being made for the purposes of a sectional blind or shutter, and I contemplate all these various adaptations of the invention in the practical embodiments of the construction now to be set forth in detail.

In the accompanying drawings:—

Figure 1 is a front elevation showing a main window frame having my invention applied thereto. Fig. 2 is a vertical sectional view taken about on the line 2—2 of Fig. 1. Fig. 3 is a perspective view of the storm window alone and illustrating the lower section thereof partially raised as when at an open adjustment, one of the lower guides being also illustrated as detached from said lower section, this mode of detachment being used when it is desired to entirely separate the lower section from the upper section of the device. Fig. 4 is a side view showing the window folded or collapsed, both sections connected, this condition facilitating the carrying of the window to and from its position for use and its place of storage when not being used.

In the drawings A denotes the main frame of a window such as is used ordinarily in the construction of dwellings. The regular vertically sliding upper sash is denoted at B and its co-operating lower sash at C. The window sill is designated at 1 and the usual guiding strips at 2. The storm window is indicated at D and is composed of the upper section 3 and the lower section 4. These sections may be in the form of a window sash, having the window panes 5, or

the sections might be solid, or slatted to provide shutters or blinds as might be found most desirable.

The sections 3 and 4 of the storm window are maintained in proper relative positions by certain members attached to the sections to connect the same together and to the main window frame A, the latter having also suitable fastening and engaging means co-operating with the parts of the storm window to prevent displacement of the latter from said frame A when once arranged in position. With the foregoing in view the upper relatively stationary section 3 is provided 15 at its opposite sides with the plates 6 extending practically the entire length thereof and having pivotally connected thereto at 7 the guides 8. The guides 8 are slotted as shown at 8' and are of angular form so that 20 the slotted flanges 8' overlap the outer side of the section 4 while the unslootted flanges overlap the side edges of said section 4. Rotatable fastenings 9 consisting of headed members of some sort are carried by the 25 lower end of the section 4 and so arranged that the heads thereof may pass through the slots 8' of the guides 8, when the heads of said members 9 are alined with the slots, a transverse arrangement of said heads, however, positively securing the section 4 to the 30 guides but permitting relative sliding movement of these parts for the purpose of raising and lowering the section 4 to control ventilation through the storm window after 35 it is placed in position on the frame A.

The storm window when arranged upon the frame A is snugly received in a sort of seat which is always provided at the outermost portion of window frames, by reason 40 of the arrangement of the sill and guide strips of such frames. Applied to the top of the frame A are detachable plates 10 and a transverse angular-shaped plate 11 is secured to the top bar of the section 3 of the 45 storm window in such a position that in placing the storm window on the frame A it is only necessary to engage the vertical flange of the plate 11 beneath the small plates 10, and force the sections 3 and 4 inward until the lower section 4 rests at its lower end on the sill 1, as seen most clearly in Figs. 1 and 2 of the drawings. To prevent unauthorized displacement of the storm window after being so arranged it is contemplated to utilize small rotary fastening members 12 which are secured to the outer surface of the frame A and capable of being turned into engagement with the guides 8, the parts 10 and 12 thus quite effectively 55 holding the storm window in position on the frame A. With the storm window adjusted in place as above described it is obvious that the lower section 4 may be readily raised by grasping the finger piece 13 (see Fig. 2) 60 whereupon the section 4 will slide vertically

between the outermost guide strip 2, the guides 8, and the upper section 3. With the section 4 upraised a short distance, and the sash B of the main window lowered, an ideal system of ventilation is afforded without liability of creating a direct draft upon occupants of a room or apartment for which the window may be provided.

In order that the storm window may afford a very effective storm-tight closure it is contemplated to provide upon the upper bar of the section 4 an angular-shaped plate 4' having a horizontal flange secured by fastenings to said section 3 and a vertical flange adapted to engage over a plate 3' secured to the lower bar of the section 3 at its inner side. The parts 3' and 4' form an effective weather strip or seal, so to speak, intermediate the adjacent ends of the sections 3 and 4.

When it is desired to remove the storm window from the frame A it is only necessary to turn the fastening members 12 into vertical positions and pull outwardly on the lower portion of the storm window until the plate 11 is disengaged from the small plates 10 at the upper end of the frame A. If now it is desired to collapse the storm window to render it easy to carry the operator will simply slide the lower section 4 upward until its plate 4' is disengaged from the plate 3', whereupon the section 4 and guides 8 will fold readily into the positions illustrated in Fig. 4. In the event, however, that the storm window is desired to be carried in sections, instead of folding the parts as in Fig. 4, the section 4 will be detached from the section 3 by merely turning the members 9 until they will pass through the slots 8' of the guides 8, whereupon the sections 3 and 4 are free to be detached from one another.

It is possible to apply the metal parts 6, 8, 3', 4' and 11 to an ordinary single frame storm window such as now in use, by merely cutting said window in half and applying filler strips to its opposite ends. Thus the ordinary storm window may readily be converted into a storm window having all of the advantages of the construction above set forth.

Having thus described my invention, what I claim as new is:

1. A storm window comprising pivotally connected and relatively slidably sections foldable one against the other to assume a collapsed condition, means whereby the window may be secured to a supporting frame, and interlocking plates at the pivotally connected portions of the sections coacting to hold the latter in extended condition.

2. A storm window comprising pivotally connected sections foldable one against the other to assume a collapsed condition, means whereby the window may be secured to a

- supporting frame, and interlocking plates at the pivotally connected portions of the sections coacting to hold the latter in extended condition, one of the sections comprising a 5 sash slideable relatively to the other section and carrying one of the interlocking plates aforesaid whereby on movement of the sash said plates may be disengaged from one another.
- 10 3. In a storm window, the combination of pivotally connected sections, one of said sections comprising slotted guide plates, a sash and fastening members on the sash passing through the slotted portions of the guide 15 plates and operable to detachably and slidably connect the sash with said plates.
4. A storm window comprising an upper section, a lower section, a pair of guides pivoted at one end to the upper section and extending along the lower section, members 20 slidably connecting the other ends of the guides to the lower section, and coöperating means between the sections normally preventing relative pivotal movement thereof.
- 25 5. A storm window comprising an upper section, a lower section, a pair of guides pivoted at one end to the upper section and extending along the lower section, and fastenings on the lower section detachably and 30 slidably connecting said section with the other ends of the guides.
6. A storm window comprising an upper section, a lower section, a pair of guides pivoted at one end to the upper section and extending along the lower section, connections 35 intermediate said guides and the lower section, and interlocking means between the adjacent ends of the said sections to hold the sections in predetermined positions.
- 40 7. A storm window comprising relatively stationary and movable sections, and members pivotally connecting said sections and comprising guides, and connections between said guides and the relatively movable section 45 limiting sliding of the last mentioned section.
8. In combination, a window frame, a storm window therefor comprising relatively stationary and movable sections, engaging means intermediate the upper portion 50 of the movable section and the relatively stationary section normally holding said sections alined, guides projecting from said stationary section, and connections intermediate said guides and the movable section permitting movement of the latter rela-

tive to the stationary section when said engaging means have been disengaged.

9. In combination, a window frame, a storm window therefor comprising relatively stationary and movable sections, guides projecting from said stationary section, connections intermediate said guides and the movable section permitting movement of the latter relative to the stationary 60 section, and other connections intermediate said guides and the stationary section permitting of folding of the movable section against the stationary section.

10. In combination, a window frame, a storm window therefor comprising relatively stationary and movable sections, guides projecting from said stationary section, connections intermediate said guides and the movable section permitting movement of the latter relative to the stationary section, other connections intermediate said guides and the stationary section permitting of folding of the movable section against the stationary section, and plates carried by the 70 adjacent ends of the stationary and movable sections and adapted to be interlocked to hold said sections in alined positions.

11. In a storm window, the combination of relatively movable and stationary sections, a pair of guide plates pivoted to the stationary section, and fastenings connecting said guide plates with the movable section and rotatable to permit of detachment of the movable section from the guide plates, 80 and connections intermediate the sections whereby the same may be collapsed one against the other.

12. A storm window comprising relatively movable and stationary sections collapsible to assume positions one against the other, slotted guide plates carried by the stationary section, fastenings on the movable section rotatable in the slotted portions of said plates whereby to slidably connect the movable section with the plates and permit detachment of said section from the plates, and weather strip means intermediate the sections coacting to interlock the latter against collapsing movement when in extended positions.

In testimony whereof I affix my signature in presence of two witnesses.
